TILE UNIT OR THE LIKE FOR FLOORS, WALLS OR OTHER SURFACES

Stephen B. Yacura, Upland, Calif.

Application August 19, 1957, Serial No. 47,416

Term of patent 3½ years

(Cl. D18—2)

The accompanying drawing is a plan view of a tile unit or the like for floors, walls or other surfaces, showing my new design, it being understood that the unit is comparatively thin and substantially planar on its reverse surface.

I claim:

The ornamental design for a tile unit or the like for floors, walls or other surfaces, as shown and described.
